(57) **CLAIM**

The ornamental design for an architectural floodlight, as shown and described.

DESCRIPTION

FIG. 1 is a front perspective view of an architectural floodlight of the present invention;

FIG. 2 is a rear perspective view of the architectural floodlight of FIG. 1;

FIG. 3 is a top plan view of the architectural floodlight of FIG. 1;

FIG. 4 is a front elevational view of the architectural floodlight of FIG. 1;

FIG. 5 is bottom plan view of the architectural floodlight of FIG. 1;

FIG. 6 is a right side elevational view of the architectural floodlight of FIG. 1, the left, opposite, side of which is a mirror image thereof; and,

FIG. 7 is a rear elevational view of the architectural floodlight of FIG. 1.

The broken lines shown are for illustrative purposes only and form no part of the claimed design.
